DESIGN FOR CHESSMEN OR SIMILAR ARTICLES

Richard W. Danon, Chicago, Ill.

Application March 7, 1938, Serial No. 75,646

Term of patent 7 years

To all whom it may concern:

Be it known that I, Richard W. Danon, a citizen of the United States and a resident of the city of Chicago, in the county of Cook and State of Illinois, have invented a new, original, and ornamental Design for Chessmen or Similar Articles, of which the following is the specification, reference being had to the accompanying drawing, forming a part thereof.

On the drawing:

The chessmen of Figures 1 to 6, inclusive, correspond and have the values and powers of the original chessmen known as the king, queen, rook, bishop, knight, and pawn, respectively.

I claim:

The ornamental design for chessmen or similar articles, substantially as shown and described.

RICHARD W. DANON.
